UNITED STATES PATENT OFFICE.

JOHN EDWARD LEVASSEUR, OF MONTICELLO, IOWA, ASSIGNOR TO GREEN-LIEF W. SIMPSON, OF SOMERVILLE, MASSACHUSETTS.

BUTTER-CAN.

SPECIFICATION forming part of Letters Patent No. 403,054, dated May 7, 1889.

Application filed March 27, 1889. Serial No. 305,016. (No model.)

To all whom it may concern:

Be it known that I, JOHN EDWARD LEVASSEUR, a citizen of the United States, and a resident of Monticello, in the county of Jones 5 and State of Iowa, have invented new and useful Improvements in Butter-Cans, of which the following, taken in connection with the accompanying drawings, is a specification.

This invention relates to improvements in 10 butter-cans for the purpose of hermetically sealing butter for transportation, storage, or otherwise, and it relates particularly to means for opening the bottom end of the can when the butter is to be used, as will hereinafter 15 be more fully shown and described, reference being had to the accompanying drawings, wherein—

Figure 1 represents a side elevation of the improved butter-can, a portion of which is 20 shown in section. Fig. 2 represents a bottom view of the same, showing a portion of its binder-strip and key or lever in section; and Fig. 3 represents a detail section on the line X X shown in Fig. 1.

25 Similar letters refer to similar parts wherever they occur on the different parts of the drawings.

a represents the can-body, having a shou- 30 dered and flaring upper end, a', adapted to receive the sink-cover in a manner somewhat similar to what is shown in the United States Letters Patent granted to me March 27, 1888, 35 No. 380,211, which cover is hermetically sealed to the upper edge of the can-body by means of suitable soft solder or alloy, c, as shown in Fig. 1.

The can-body a has near its lower end an annular swell shoulder or projection, a'', as shown in Figs. 1 and 3, and to the lower end 40 of said can-body is loosely fitted the detachable bottom d, provided at its circumference with an upwardly-projecting annular rim, d', adapted to pass outside of the lower edge of the can-body, as shown in the drawings.

45 e is a metal binder-strip that is soldered to the annular projection a'' and outside of the rim d' of the bottom d by means of soft solder or alloy, f f, (shown in Figs. 1 and 3,) which strip, after passing completely around said 50 projection and bottom rim, terminates as a tongue or flap, e', that is secured in a suitable

manner to the angular or knee-shaped key or lever g, preferably provided in its vertical portion with a slotted perforation, g', through which the tongue or flap e' is passed, as shown, 55 and preferably secured at this place to the said key by means of soft solder or alloy or other equivalent means. The horizontal portion of the said key is preferably made T-shaped, as shown at g'' in the drawings, and 60 adapted to lie flush against the under side of the bottom d, as shown, so as to be out of the way without offering any obstruction on the under side of the can, as shown.

The end of the tongue or flap e' is prefer- 65 ably united to the binder-strip e by means of soft solder or alloy, as shown at h in Fig. 2, so as to prevent its being accidentally ripped off while handling or transporting the can.

Before filling the improved can the bottom 70 d is hermetically secured to the lower portion of the can-body by means of the binder-strip e and the solder f f and the angular key secured to the tongue or flap e', as above described, after which the butter is packed into 75 the can and the sink-cover b hermetically sealed and secured to the upper end of said can-body, as mentioned, care being taken to exclude all or nearly all of the air from within the now filled can.

80 To open the can it is preferably turned upside down, and by turning the horizontal portion of the key g in the direction as shown by arrow in Fig. 2 the binder-strip e will be gradually detached from the annular projec- 85 tion a'' and bottom rim, d', as it is being wound upon the vertical portion of said key or lever, and when completely removed from its attachments to the can-body and bottom d the latter may be freely detached from the 90 can-body, and after a sufficient quantity of the contents of the can has been removed the bottom d can be put in place on the edge of the can-body, so as to serve as a removable top or cover until the can is emptied. By this 95 construction and arrangement a ready means is always at hand for the opening of the can without the aid of a special can-opener tool.

Having thus fully described the nature, construction, and operation of my invention, I 100 wish to secure by Letters Patent and claim—
The can-body having a permanently at-

tached cover, *b*, in its upper end and a detachable bottom, *d*, adapted to fit against and around its lower end, combined with a soldered metal binder-strip, *e*, having flap or tongue *e'*, and an angular key secured to said flap and having its lower portion adapted to lie against the under side of the can-bottom, substantially as and for the purpose set forth.

In testimony whereof I have signed my name to this specification, in the presence of two ¹⁰ subscribing witnesses, on this 13th day of March, A. D. 1889.

JOHN EDWARD LEVASSEUR.
